HINGE FOR A PIVOTAL BEDFRAME

Melvin E. Roche, Berea, Ohio

Original No. 185,173, dated May 12, 1959, Ser. No. 48,782, Dec. 5, 1957, for 14 years. Application for reissue Dec. 17, 1959, Ser. No. 58,711. Term of patent 14 years.

(Cl. D5—2)

Matter enclosed in heavy brackets [ ] appears in the original patent but forms no part of this reissue specification; matter printed in italics indicates the additions made by reissue.

In Fig. 1 of the drawing, a novel hinge for a pivotal bedframe is shown in perspective. *The dominant feature of the hinge is shown in full lines.* An associated

2

bed headboard leg and frame runner are shown in dot-dash lines with the novel hinge for illustrative purposes only.

Fig. 2 shows the hinge of Fig. 1 in perspective and in a closed position.

Portions of the drawings are stippled to indicate contrast in surface materials.

I claim:

The ornamental design for a hinge for a pivotal bedframe, as shown and described.
